METHOD AND APPARATUS FOR DRYING
PRINTING INKRobert Helmer, Douglaston, N. Y., assignor to
The International Printing Ink Corporation,
New York, N. Y., a corporation of Ohio

Application December 26, 1935, Serial No. 56,244

12 Claims. (Cl. 34—48)

This invention relates to a method and apparatus for drying printing ink, and aims to accelerate the process of printing.

There are now available so-called "quick drying" printing inks whose vehicles consist of a binder dissolved in a solvent whose vapor pressure curve is such that the solvent is substantially non-volatile at ordinary room temperature (about 25° C.) and becomes a highly volatile liquid at temperatures of about 150° C. The customary method of drying such inks is to apply heat to the paper on which the ink has been printed to raise the paper and ink to a temperature of about 150° C. This temperature is sufficient to vaporize the solvent in the ink and insufficient to injure the paper. In carrying out this method, it has been customary to heat the paper from the back or unprinted side, usually, by contact with a solid heat-conducting member such as a hot metal drum, or by means of hot air. In both cases, the temperature of the heating means (hot drum or hot air) has been limited to a temperature which cannot injure the paper. This limitation of the temperature of the heating means makes it necessary to apply the heat for a substantial period in order to raise the paper and the ink to the temperature at which the solvent in the ink is highly volatile and to volatilize the solvent.

I have discovered that, on the application of intense heat to printed matter consisting of paper printed with a quick drying ink of the type referred to, the period of time required to raise the solvent in the ink to the temperature at which it volatilizes rapidly and to volatilize substantially all of the solvent in the ink is materially shorter than the time required to char or burn the paper. My method consists in drying printing ink by the application to the printed matter of a heat so intense that it is capable of raising the temperature of the paper far above its scorching point, while at the same time limiting the period of the application of such heat to a time which is sufficient to volatilize substantially all of the solvent of the ink and less than the time which would be required to char or burn the paper. The heat applied in this method may be above the ignition point of the vapor of the ink solvent, so that at least some of the solvent vapor from the ink is ignited and burned, but neither the paper nor the binder in the ink which binder may be highly inflammable is burned or otherwise injured.

In accordance with my invention, the intense heat is applied to the printed surface of the

printed matter in the form of hot gas or radiant heat, or most desirably both, and the period of application of the heat to each part of the surface of the printed matter is limited by relative movement between the heat-applying means and the printed matter.

My invention includes also apparatus by means of which my method may be carried out efficiently and safely.

In the form which I now consider most desirable, the apparatus includes a closed furnace, one wall of which is provided by a traveling web of paper bearing the ink to be dried. The opposite wall of the furnace carries the heat-applying means which direct an intense heat against the printed surface of the web. This wall is so arranged that it may be opened to direct the heat-applying means away from the web in order to avoid scorching the web when the web is stationary. The opening means are most desirably operatively connected with the means for causing the travel of the web across the furnace in such a way that opening of the furnace occurs automatically when the movement of the web is stopped.

A specific embodiment of the apparatus features of my invention is illustrated in the accompanying drawings, in which

Fig. 1 is a side elevation of the complete apparatus, omitting parts of the printing press which are of standard construction and showing the furnace in longitudinal section;

Fig. 2 is a diagrammatic view containing an enlarged side elevation of the furnace taken from the opposite side from Fig. 1 and an enlarged side view of the means for supplying gas and air to the furnace, and showing the electrical connections;

Fig. 3 is an enlarged transverse section of the furnace taken on the line 3—3 of Fig. 1;

Fig. 4 is a further enlarged section taken on the line 4—4 of Fig. 3 and showing the details of one of the burners, and indicating in dotted lines the position of this burner when turned away from the web;

Fig. 5 is an enlarged section taken on the line 5—5 of Fig. 1, showing the air control valve, and

Fig. 6 is a diagram of the electric control.

The apparatus illustrated includes a printing press 10 of standard construction for printing on a web P of paper. Ink is applied to the web of paper P in the press. The web emerges from the press over a roller 11 with its printed side uppermost, and, after the drying of the ink by 55

the apparatus to be described, the web P is wound up on a rewind roller 12 which constitutes a part of the printing press. The rewind roller and the other rollers of the press are driven by a three-phase electric motor indicated diagrammatically at 13 in Fig. 2. The customary means are provided for regulating the speed of the press which determines the speed of travel of the web P.

In its travel between the guide roller 11 of the press and the rewind roller 12 of the press, the web P passes over guide bars 14 and rollers 15, 16, 17, 18 and 19 mounted on a frame 20.

A furnace 30 is mounted on horizontal bars 21 of the frame 20 above and adjacent to a portion of the web traveling between the rollers 11 and 15. The furnace is enclosed by side walls 31, end walls 32, 32', a top wall 33, and the portion of the web P between the end walls 32 which constitutes the bottom wall of the furnace. The end walls 32 and 32' terminate a short distance above the surface of the web. The top wall 33 contains three doors 34, which carry series of radiant gas burners 35 which are directed towards the web P when the doors 34 are closed. Each row of burners 35 is mounted on a pipe 36. Each pipe 36 is attached at one of its ends to a supply pipe 37 through a stuffing box 38 in such manner that each pipe 36 may be rotated about its own axis. Each pipe 36 thus serves as a pivot about which one row of burners 35 and one door 34 may be rotated between a position in which the doors are closed and the burners are directed towards the web P (shown in full lines in Figs. 1, 3 and 4 and in dotted lines in Fig. 2) and a position in which the doors are open and the burners are directed away from the web (shown in dotted lines at the top of Fig. 2 and in dotted lines in Fig. 4).

Means are provided for simultaneously opening and closing the three doors 34 and for swinging the three rows of burners 35 away from and towards the web. Such means include radial arms 68 fixed on the pipes 36, and connected by links to a swinging bar 70 provided with a handle 70', so that, when the bar 70 is in the position shown in full lines in Fig. 2, the pipes 36 are turned so as to close the furnace and direct the burners towards the web P and, when the bar 70 is swung to the position shown in dotted lines in Fig. 2, the pipes are turned into a position in which the furnace is open and the burners are turned directly away from the web.

Each of the burners 35 includes a nipple 39, a deflector 40, and a parabolic radiator 41 of refractory material which is heated to incandescence by the gas flame issuing from the nipple and serves to direct the flame and radiant heat along the axis of the burner and, therefore, directly against the web when the burner is turned towards the web, as shown in Fig. 4.

A mixture of gas and air is supplied to the burners through the pipes 36 and supply pipes 37 from a mixing chamber 42. The gas and air are supplied under pressure to the mixing chamber and the burners by a centrifugal pump 43, which draws air from the atmosphere through a pipe 44 and gas from a gas main 45.

After passing under and across the furnace 30, the web P passes through a suction duct 50 formed by an upper wall 51, a lower wall 52, an end wall 53, and the end walls 32' of the furnace. The suction duct 50 is open at one side of the furnace and at the other side is connected to a conduit 54 containing an exhaust 75 fan (not shown).

When the furnace is closed, the burners 35 direct intense heat toward the printed surface of the web P, which would char and burn the web if any portion of the area of the web were exposed to it for more than a very brief period 5 of time. It is, therefore, essential that this supply of intense heat to the web be stopped when the movement of the web is stopped. This may be accomplished in the form of apparatus illustrated by rotating the pipes 36 to open the doors 10 34 and direct the burners away from the web. It is desirable that automatic means should be provided for opening the furnace when the web is stationary and closing it when the web is put in motion. Such means are illustrated in Fig. 2 15 and Fig. 6.

Fig. 2 shows diagrammatically the main switch 60 of the press 10 which serves to connect the motor 13 of the press with supply lines 61. When the switch 60 is open, the web is stationary and, when the switch 60 is closed, the web is put in motion by the motor 13 which drives the rewind roller 12 and the other rollers 20 of the press.

The closing of the switch 60 energizes a control circuit 62 having two parallel branches one of which, 63, controls a small motor 66 carrying a pinion meshing with a gear 73 fixed on the middle one of the pipes 36. When the circuit 63 is energized by closing the switch 60 with 30 the furnace open, the motor 66 acting through the gear 73 turns all the pipes 36 to swing the burners downward towards the web and to close the doors 34. Thus, the furnace is closed and the burners directed towards the web when the web is put in motion by closing the switch 60 and energizing the motor 13. If the web is stopped by opening the switch 60, or by any means cutting off the current from the motor 13, the circuits 62 and 63 are de-energized. 40 This causes operation of the motor 66 in the reverse direction to open the furnace and direct the burners away from the web.

Details of the mechanism which controls the motor 66, are shown in Fig. 6. The circuit 63 45 contains an electro-magnet 67 and this magnet and a spring 68 control the position of a reversing switch 69 connected between the motor 66 and a supply line 90. Rotation of the motor 66 in either direction beyond the points at which it directs the burners towards and away from the web is prevented by the opening of switches 80 controlled by cams 81 mounted on the middle pipe 36.

In order to save fuel, it is desirable that the supply of gas to the burners be reduced when the furnace is opened. For this purpose, an automatic electric valve 75 of standard construction is placed in the gas supply pipe and connected in a branch 76 of the circuit 62. The valve 75 is opened only when the circuit 76 is energized. Closing of the valve 75 by de-energizing the circuit 76 also closes a butterfly valve 77 in the air pipe 44 which is connected to the mechanism of the valve 75 by a link 78. To prevent extinguishment of the burners when the valves 75 and 77 are closed, a small by-pass 79 is provided around the valve 75 and a small opening 80 is provided in the butterfly valve 77. This by-pass and this opening insure a sufficient supply of air and gas to the burners to keep them ignited and the refractory radiators incandescent when the web is stationary and the burners are turned away from the web.

A specific example of the practice of my 75

method by means of the apparatus as described is as follows: An ink whose vehicle consists of a solution of a binder such as nitrocellulose in a volatilizable solvent such as diethylene glycol monobutyl ether or diethylene glycol monobutyl ether acetate is applied to the upper surface of the web ¹⁰ P in the press ¹⁰. As each successive part of the web is drawn through the furnace ³⁰, intense gaseous and radiant heat are directed ¹⁰ against the printed surface of the web by the radiant gas burners ³⁵. The solvent in the ink is vaporized and ignited as the web passes through the furnace. The products of combustion are drawn out of the furnace under the end wall ¹⁵ ^{32'} and through the suction duct ⁵⁰, so that they do not contaminate the air of the press room. Any vapor which may come off the web after it leaves the furnace is also drawn out through the duct ⁵⁰. Although combustion, both of fuel ²⁰ gas and of the solvent vapor, is constantly taking place in the furnace, the paper web is not burned, charred or injured in any way because the period during which any area of the web is within the furnace is extremely short, amounting ²⁵ in practice to about one-third of a second. The paper of the web is, of course, heated to a considerable extent during the passage of the web across the furnace and the tensile strength of the web might be reduced if the web were allowed to remain hot. The web is, however, cooled during its passage over the rollers ¹⁶, ¹⁷, ¹⁸ (which are preferably water-cooled rollers) before it is wound up on the rewind roller ¹². When the travel of the web is stopped for any reason, ³⁰ the furnace is immediately opened and the burners are directed away from the web so that the web is not burned.

In the apparatus described, the radiant burners ³⁵ apply intense heat to the web both in the form of radiant heat and in the form of hot gas. This causes a very rapid volatilization of any volatilizable solvent contained in the ink. If the solvent is inflammable, a considerable part of it is ignited and burned in the furnace. The products of combustion, as well as any part of the solvent vapor which is not burned, are drawn off through the suction duct ⁵⁰ to a point remote from the web.

It is not essential that both radiant heat and ⁵⁰ gaseous heat be used. I have found it satisfactory to use gaseous heat only, but in this case burners ejecting large gas flames under heavy pressure are used and substantially all the solvent which is driven from the ink on the web is ignited ⁵⁵ and burned.

The drying of the ink by this method is extremely rapid and permits use of the method with rotary presses operating at a speed of 400 feet per minute.

My invention is by no means limited to the use of the method or the apparatus with the particular ink which has been mentioned for the sake of illustration. It has proved effective by drying and accelerating the drying of many types of inks, including several which cannot be satisfactorily dried by the hot roll method.

What I claim is:

1. Apparatus for drying printing ink comprising the combination with means for causing a traveling movement of a web of paper to which the ink has been applied, of an enclosed furnace located adjacent to the printed side of the web so that the web forms one side of the furnace, and means for opening the opposite wall of the ⁷⁵ furnace.

2. Apparatus for drying printing ink comprising means for causing a traveling movement of a web to which the ink has been applied, a turnably mounted heater located adjacent to the web, and means operatively connected with the ⁵ means for causing travel of the web for directing said heater towards the web when the web is in motion and away from the web when the web is stationary.

3. Apparatus for drying printing ink comprising means for causing a traveling movement of a web of paper to which the ink has been applied, an enclosed furnace located adjacent to the printed side of the web so that the web forms one wall of the furnace, and an automatic ¹⁵ means for opening the opposite wall of the furnace when the traveling movement of the web is stopped.

4. Apparatus for drying printing ink comprising the combination with means for causing ²⁰ travel of a web to which the ink has been applied, of a gas burner located adjacent to a point of the travel of the web and mounted for rotation about an axis transverse the path of the web so that it may be directed towards or away from ²⁵ the web.

5. Apparatus for drying a printing ink comprising a combination with means for causing the travel of a web to which ink has been applied, of a heater adapted to apply intense heat to the ³⁰ printed side of the web at a point in its travel, said heater being mounted for rotation about an axis transverse the path of the web so that it may be directed towards or away from the web.

6. In a web printing press, apparatus for drying printing ink comprising means for causing a traveling movement of the web to which the ink has been applied, a movable heater, and means operatively connected with the means for causing travel of the web for moving said heater to ⁴⁰ an operative position when traveling movement is imparted to said web so that intense heat is directed upon the printed surface of the web and to an inoperative position when the movement of said web is stopped. ⁴⁵

7. Apparatus for drying printing ink comprising the combination with means for causing a traveling movement of the material to which the ink has been applied, of a furnace, a heater attached to one wall of the furnace and adapted ⁵⁰ to direct intense heat upon the printed surface of the material, and automatic means for opening the furnace wall to which said heating element is attached.

8. Apparatus for drying printing ink comprising the combination with means for causing a traveling movement of a web to which the ink has been applied, of an enclosed furnace having a heating compartment and a separate suction compartment located adjacent to the printed side ⁶⁰ of the web so that the web forms one wall of the furnace.

9. The method which comprises printing at room temperature with an ink containing a combustible binder dissolved in a volatilizable and ⁶⁵ inflammable solvent which is substantially non-volatile at room temperature, and then applying to printed ink through a gaseous medium heat of sufficient intensity to volatilize the ink solvent instantaneously and ignite the solvent vapor, and ⁷⁰ limiting the time of application of said heat to a period so short that the heat does not char the ink binder.

10. The method which comprises printing on a combustible material with an ink containing a ⁷⁵

- combustible binder dissolved in a volatilizable and inflammable solvent which is substantially non-volatile at room temperature, moving the printed material away from the printing means, 5 applying through a gaseous medium to the printed surface of the material heat of sufficient intensity to volatilize the solvent and ignite the solvent vapor, maintaining the material out of contact with any heated surface between printing 10 and the application of said heat, and limiting the time of application of said heat to each part of this surface of the material to a period so short that the heat does not char the material and the ink binder deposited thereon.
- 15 11. Apparatus for drying printing ink, comprising means for causing a traveling movement of a combustible web to which the ink has been applied, an enclosed furnace located adjacent to the traveling web so that its printed side is exposed to the furnace heat, means for maintain-

ing the furnace temperature above the combustion temperature of the web, and means operatively connected to the means for causing travel of the web for reducing the furnace temperature to a temperature below the scorching temperature of the web when the traveling movement of the web is stopped. 5

12. Apparatus for drying printing ink, comprising the combination with means for causing a traveling movement of the material to which the ink has been applied, of a plurality of rows of heaters adapted to direct intense heat toward the printed side of the material, each of said rows being mounted for rotation about an axis parallel with the axis of rotation of each other row so that 15 the heaters may be directed toward or away from the material, said axes all lying in a plane parallel to the printed surface of said material.
